UNITED STATES PATENT OFFICE.

HENRY GRANT WALKER, OF NEW YORK, N. Y.

DOUBLE-ACTING ROCK-DRILL.

SPECIFICATION forming part of Letters Patent No. 354,957, dated December 28, 1886.

Application filed March 16, 1886. Serial No. 195,390. (No model.)

To all whom it may concern:

Be it known that I, HENRY GRANT WALKER, a citizen of the United States, and a resident of New York, in the county and State of New

York, have invented certain Improvements in Double-Acting Rock-Drills, of which the following is a specification.

My invention relates especially to devices employed for drilling rock, &c., and has for its object the provision of a drill which may be run by hand-power in an easy and effective manner.

To attain the desired end my invention consists, essentially, in a main frame or case mounted upon an adjustable weighted tripod in the usual manner, in combination with two sleeves, the opposite extremities whereof consist of cams. The sleeves are made to revolve by suitable mechanism in opposite directions when the driving-crank is turned. The above-mentioned sleeves revolve upon a central sleeve wherein the drill-shaft plays, said drill-shaft being preferably raised by the movement of the cam-surfaces over each other and forced downward both by gravity and by springs encircling the drill-shaft; and my invention also involves certain other novel and useful combinations or arrangements of parts and peculiarities of construction and operation, all of which will be hereinafter first fully described, and then pointed out in the claims.

In the drawings, Figure 1 is a side elevation of my improved double-acting drill, and Fig. 2 is a plan view thereto. Fig. 3 is a vertical axial sectional view of the driving mechanism.

Like letters of reference, wherever they occur, indicate corresponding parts in all the figures.

A are the legs of the tripod, made in the usual manner and bearing adjustable weights B, said legs being pivoted to the main frame at C.

D is a bevel gear-wheel mounted upon a sleeve, E, passing through a perforation in the top of the main frame. A flange, F, secured to wheel D, permits the same to revolve, while holding it against displacement. Feathers G upon wheel D fit into grooves H, upon each side of sleeve E, thus causing it to rotate with wheel D, while permitting a perpendicular movement. The lower extremity of sleeve E is provided with two or more cams, e. I is a sleeve or cylinder extending through the main frame

and sleeve E. Located below sleeve E is a second sleeve, E', bearing a fixed bevel-wheel, D'. The upper extremity of sleeve E' also terminates in cams e'.

K is a driving-crank attached to a shaft, L, extending through the main frame and bearing upon its inner extremity a bevel-wheel, M, the teeth whereof engage either directly with the bevel-wheels D and D', or with intermediate wheels, N, as in Fig. 1.

By varying the size of wheels M and N the speed and power of the drill may be varied to suit the work to be performed.

Playing within the cylinder I is a drill-shaft, P, screw-threaded, as shown, and provided at the upper surface of the main frame with a feed-nut, Q, bearing a projecting arm, R. An adjustable upright, S, affixed to the main frame, engages with arm R when the drill is depressed, preventing the turning of the nut; but as the drill-shaft is raised the arm is released, and the nut turns with the drill, the drill-shaft being turned, preferably, by friction contact of the sleeve E with the nut Q, or, as shown in Fig. 2, by a feather, e', upon the sleeve E, fitting into a groove, p, in the drill-shaft P. By raising or lowering upright piece S the turning of the nut may be accurately regulated. T is a washer beneath nut Q, which receives the nut and prevents it striking sleeve E when the drill falls.

U is a spring, made in three sections, coiled about shaft P, said springs, together with the weight of the drill, regulating the stroke. I make this spring in three sections, in order that when one is worn out or broken it may be replaced without the expense of an entire new spring. Washers s are located between the sections to insure a proper action. The upper end of the spring bears against the upper end of the cylinder I at i', and the lower extremity against a milled nut, i'', placed on the thread of shaft P.

The drill is held in place by means of a bevel-nut, p', engaging with the lower extremity of shaft P, a jam-nut, W', engaging with nut p' at its lower extremity. The cylinder I is perforated at Y, and the milled nut i'', playing upon shaft P, provides means for adjusting the tension of the spring.

When constructed and arranged in accordance with the foregoing description, the action

of my improved drill is as follows: When the crank is turned, the cam sleeves E and E' are caused to revolve in opposite directions, the upper sleeve being raised by such movement, 5 carrying the drill-shaft with it, gravity and the spring forcing the drill downward as the cams pass the point of engagement. By varying the number of cams the power and number of strokes may be varied; but by my peculiar construction 10 I am enabled to increase the number of strokes to each revolution of the driving shaft, greatly adding to the speed with which work may be performed. When it is desired to raise the drill from the hole and prevent the 15 operation of the cams, a wedge or block, V, is inserted, as illustrated in Fig. 1, permitting the free turning of the drill shaft, and by holding the feed-nut the shaft will rise when the crank is turned.

Having now fully described my invention, what I claim as new therein, and desire to secure by Letters Patent, is—

1. In a rock-drill, the combination, with the supporting-frame and drill-shaft surrounded by a spring within the frame, of the two sleeves, 25 the ends whereof are provided with cams, as set forth, said sleeves revolving in opposite directions through the medium of the driving mechanism connected therewith, substantially as shown and described.

2. The combination, with the supporting-frame wherein are located the wheels M and N, of the cam-wheel bearing the fixed wheel, the cam-sleeve having grooves wherewith feathers 35 upon the wheel D engage, and the drill-shaft

surrounded by a spring, U, within the frame, substantially as shown and described.

3. The combination, with the supporting-frame and driving mechanism, and the cam-sleeves, of the drill-shaft, cylinder I, and spring 40 U, surrounding the drill-shaft within the supporting-frame, arranged substantially as shown and described.

4. In a rock-drill of the character herein specified, the combination, with the drill-shaft, 45 of the spring U, made in sections, the end of the lower section bearing against a nut, ν , and the end of the upper section against cylinder I, substantially as and for the uses and purpose shown and described.

5. A double-acting rock-drill consisting of a tripod supporting a main frame, two cam-sleeves revolving in said frame, as set forth, mechanism for driving said cam-sleeves, a screw-threaded drill-shaft bearing a feed-regulating nut and passing through a cylinder whereon the cam-sleeves revolve, and a sectional spring surrounding the drill-shaft within the cylinder, bearings being provided for said spring, the whole combined and arranged to 60 operate substantially as shown and described.

In testimony of the foregoing specification I do hereby sign the same, in the city of New York, in the county and State of New York, this 2d day of March, A. D. 1886.

HENRY GRANT WALKER.

In presence of—

JAS. B. KILSHEIMER,
JOHN MORRIS.
